UNITED STATES PATENT OFFICE.

LOUIS B. BENDER, OF WASHINGTON, DISTRICT OF COLUMBIA.

ELECTRICAL SIGNALING.

Application filed August 29, 1923. Serial No. 659,971.

To all whom it may concern:

Be it known that I, LOUIS B. BENDER, a citizen of the United States, residing at Washington, in the District of Columbia, 5 have invented certain new and useful Improvements in Electrical Signaling, of which the following is a specification.

This invention relates to an improved system for the transmission and reception of 10 radio signals.

The object of this invention is to provide a radio system whereby the signals transmitted, the dots and dashes, are of the same intensity and same time duration and characterized by a difference in carrier 15 frequency.

In a paper published in the Journal of the Franklin Institute, May, 1923, Gen. G. O. Squier proposed a new telegraph transmission system in which the dots and dashes of the Morse code are of the same time duration and differentiated by a difference in intensities thereby securing a higher speed signaling, the dash signals not requiring more 20 time than the dot signals. This invention is a modification of the system proposed by General Squier providing the improvement of having the same signal intensity for the dot and the dash and effecting a differentiation between them by a difference in frequencies.

To accomplish this result I propose to provide at the transmitting station a C. W. radio transmitter capable of generating and 35 radiating two radio frequencies, the change from one frequency to another being obtained by a change in one of the constants of the oscillating circuit, the radio frequency current being modulated by a current of low frequency, sine wave form.

At the receiving station I propose to provide two receiving systems, each being tuned to receive a signal of a different frequency, that is, one system responding only to the 45 dot frequency signal and the other responding to the dash frequency signal.

In order that my invention may be more clearly understood, it is described in more detail with the aid of the accompanying drawings, in which—

Figure 1 represents the character of transmitted signals using different carrier frequencies for dots and dashes and these carriers modulated by a low frequency of sine wave form without spacing between ele-

ments of a letter, but with one half cycle between letters themselves. After rectification in the receiving system, only the upper or lower half of the envelope would remain.

Figure 2 shows the necessary combination of C. W. radio transmitter, automatic tape transmitter and modulation generator wherein the tape transmitter controls the oscillation of the radio transmitter at two frequencies or prevents oscillation entirely.

Figure 3 shows the essential elements and arrangement of the receiving system required for receiving and recording modulated radio signals at two carrier frequencies.

Referring more particularly to the drawings, T in Figure 2 represents a C. W. radio transmitter of any form in which an inductance E is so connected as to control the oscillation of the system and the frequency of the oscillations. C represents the feed wheel of an automobile tape transmitter, S the punched tape being fed through the automatic tape transmitter, Y and X the pecker pins of this transmitter which come into contact with Z when the punched tape will permit. When neither Y nor X is in contact with Z, the circuit through E is open and no oscillation generated. This is the condition existing when spaces between letters and words on the tape are passing under Z. When a perforation in the tape S permits pecker pin Y to come into contact with Z, the oscillating circuit is completed through the whole of inductance E and a definite radio frequency is generated and radiated from the antenna N. This is the condition existing when a perforation representing a dot is passing under Z. When pecker pin X comes into contact with Z, only a portion of inductance E is in circuit and a higher radio frequency is generated and radiated.

This is the condition when a perforation representing a dash is passing under Z. The tape is so perforated that pecker pins X and Y can never be in contact with Z at the same time. The feed wheel C is driven at constant speed by any convenient form of motor M. Coupled to the feed wheel C through adjustable coupling K is a single phase, low frequency generator D which generates a current wave of substantially sine form. The output of generator D is connected to the modulation transformer F of the radio transmitter T. The coupling K

55 60 65 70 75 80 85 90 95 100 105 110

is so adjusted that full modulation and minimum radiation of the radio frequency energy from transmitter T occurs just as the tape S disengages one pecker pin (X or 5 Y) from contact with Z and permits a new engagement. Zero modulation and maximum radiation occurs midway between the pecker-pin contacts.

The receiving equipment required by this 10 system is shown in some detail in Figure 3. Two separate antennæ H and H', are connected to separate tuners, amplifiers and detectors J and J', the two receiving systems being separately tuned for two different frequencies, one for the dash frequency and the other for the dot frequency. After amplification and rectification, the received energy is led to a sensitive relay of the suspended coil type P which carries a contact 15 maker K on a contact block A. There are two independent coils in the moving system, one coil being connected to J and the other to J' in such manner that energy from J will deflect the pointer K to the right and 20 energy from J' will deflect it to the left or vice-versa. The pointer K normally rests on an insulating section separating the two contact surfaces of the block A. When the pointer K is deflected to the right the potential of battery C is applied to the grid of 25 vacuum tube O with respect to its filament. This action results in a flow of current in the plate circuit of tube O through relay M. The latter relay is then closed and completes 30 a circuit from the battery E through the variable resistance R and the coil B of a siphon recorder or similar recording mechanism. Adjustment of the variable resistance R permits any desired amplitude of 35 signal to be recorded on the tape Q. Deflection of the pointer K to the left results in similar action of the vacuum tube O' and relay M', the variable resistance R' permitting adjustment of the amplitude of the 40 recorded signal. These resistances R and R' furnish the means of adjusting the relative height of the recorded signals and thereby making the Morse code reappear. A condenser in series with a resistance is 45 shunted across the winding of each relay M and M' to improve the operation. The output circuits of J and J' may be connected directly to the coils of relay P as shown in Figure 3 or may be connected thereto, 50 through transformers. In the former case, the relay P would be actuated by the reduction in plate and coil current due to a received signal; in the latter case, the coils of relay P would carry no current until the 55 signal was received and the action would be direct. The modulation frequency is limited only by the inertia of the moving parts in the transmitting and receiving apparatus.

In this system, each half cycle of the modulated current represents an element of the

Morse code. No time interval separates the elements of a letter, the elements of letters following each other without spacing. Between letters, words, and sentences, time intervals equal to some multiple of the time unit represented by one half cycle on the modulation generator are employed. During these intervals the radio transmitter is not radiating energy, the unpunched tape at the 70 automatic tape transmitter preventing oscillation of the antenna circuit.

A telegraphic printer designed to operate on Morse code signals, such as the Creed Printer and similar designs, may be substituted for the siphon recorder with only a 80 slight modification of the printer mechanism.

I claim:

1. In a system of telegraphy, means for transmitting and receiving two radio frequency currents modulated by a low frequency alternating current of constant amplitude, said means consisting of a C. W. radio transmitter and automatic tape transmitter, a sine wave generator of low frequency, means for maintaining said generator in synchronism with said tape transmitter, and a receiving apparatus consisting of two receivers tuned to receive signals of different carrier frequencies, both of said receivers being connected to a single relay of the suspended double coil type having a contact maker moving over a double contact block, each of the two sections of said block being connected through vacuum tube relays, to a single siphon recorder for recording on a tape the received signals. 90

2. In a system of telegraphy, means for transmitting and receiving two radio frequency currents modulated by a low frequency alternating current of constant amplitude, said means consisting of a C. W. radio transmitter, an automatic tape transmitter, a sine wave generator of low frequency, means for maintaining said generator in synchronism with said tape transmitter, and a receiving apparatus consisting of two receivers tuned to receive signals of different carrier frequencies, both of said receivers being connected to a single relay of the suspended double coil type having a contact maker moving over a double contact block, each of the two sections of said block being connected through mechanical relays to suitable mechanism for recording on a tape the received signals, the pointer on said contact block being thrown in opposite directions by the two radio frequency signals, and the two signals being distinguished on the tape of the siphon recorder by their distinctive amplitudes obtainable by adjustment of resistances in the relay circuits actuating said recording mechanism. 100

In testimony whereof I affix my signature,
LOUIS B. BENDER,
